Inventor John B. Bell

United States Patent Office.

JOHN B. BELL, OF PITTSBURG, PENNSYLVANIA.

Letters Patent No. 98,735, dated January 11, 1870.

IMPROVEMENT IN MACHINE FOR JOINTING BARREL-STAVES.

The Schedule referred to in these Letters Patent and making part of the same

To all whom it may concern:

Be it known that I, JOHN B. BELL, of Pittsburg, in the county of Allegheny, and State of Pennsylvania, have invented a new and useful Improvement in Machine for Jointing Staves for Barrels, Casks, &c.; and I do hereby declare that the following is a full, clear, and exact description thereof, reference being had to the accompanying drawing, and to the letters and figures of reference marked thereon.

The nature of my invention consists in the feeding-frame, constructed, arranged, and operating in combination with a vertical cylinder, provided with cutting-bits, as hereinafter described.

To enable others skilled in the art to make and use my invention, I will proceed to describe its construction and operation.

In the accompanying drawings, which form part of my specification—

Figure 1 is a side elevation of my improvement in machine for jointing staves.

Figure 2 represents a top view or plan of the same, with the upper portion of the frame removed.

In the accompanying drawings—

A B C represent the several parts of the frame, in which the cylinder D rotates.

e represents the cutting-knives or bits, which are arranged in the face of the cylinder D, obliquely to its longitudinal plane, and at an angle to its face corresponding to the back inclination of the bit of the ordinary "hand-plane."

By thus arranging the knives or cutting-bits, their cutting-action will be from the centre of the edge of the stave and toward each end of it, the cutting being on an oblique line, and with the grain of the wood.

The inner ends of the knives should project past each other, as shown in fig. 1, and the desired cutting-set given by means of a suitable gauge.

The cylinder D is gradually contracted toward the centre, as indicated by the dotted lines 5. This contraction of the cylinder must correspond to the bilge of the stave.

The frame or bench f, for supporting and holding

the stave while being jointed, is pivoted in the ends A and B of the frame in which the cylinder rotates, and is provided with a clamping-lever, g, points 3, and a notch, 2.

The distance from the point of pivot 6 to the face 8, of the frame or bench, should be equal to half the diameter of the keg, barrel, or cask, for which the stave is intended. By thus arranging the frame or bench, the cutting-action of the knives or bits will be on a line at right angles to a line radiating from the centre of the cylinder, as indicated by dotted lines 4 in fig. 2.

The operation of my improved stave-jointing machine is as follows:

The stave s is placed on the frame or bench f, the lower end of the stave is placed in notch 2, and, by pressing on lever g, the stave will be held firmly in notch 2, and forced against the face 8 of the frame or bench, and the points 3 will prevent any side movement. Now, by turning the frame or bench f to the right, and then to the left, against the cylinder D, as indicated by the dotted lines x¹ and x², the edge of the stave will be perfectly and uniformly dressed, and jointed.

The cylinder D should be rapidly rotated, and may be placed in a vertical or horizontal position, and be provided with one or more frames or benches f, so that one or more persons, at the same time, may joint staves.

The frame or bench f may be so constructed as to adapt it to staves of different lengths, and so pivoted that in jointing the stave, the outside portion of the seam, between the staves, may be open or otherwise.

Having thus described my improvement, What I claim, is—

The pivoted frame f, constructed, arranged, and operating as herein described, in combination with the cylinder D, as and for the purpose set forth.

JOHN B. BELL.
